US00D493169S1

(12) **United States Design Patent** (10) Patent No.: **US D493,169 S**
Cheng (45) Date of Patent: **** Jul. 20, 2004**

(54) **WIRELESS NETWORK NODE DEVICE**

(75) Inventor: **Roman Cheng, Chung-Ho (TW)**

(73) Assignee: **Sendfar Technology Co., Ltd. (TW)**

(**) Term: **14 Years**

(21) Appl. No.: **29/195,047**

(22) Filed: **Dec. 5, 2003**

(51) LOC (7) Cl. **14-02**

(52) U.S. Cl. **D14/357**

(58) Field of Search **D14/136, 156,
D14/348, 363, 365, 367; 455/90.3**

(57) **CLAIM**

The ornamental design for wireless network node device, as shown and described.

DESCRIPTION

FIG. 1 is a perspective view of wireless network node device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
